UNITED STATES PATENT OFFICE.

JOHN F. O'CONNOR, OF CHICAGO, ILLINOIS, ASSIGNOR TO W. H. MINER, INC., OF CHICAGO, ILLINOIS, A CORPORATION OF DELAWARE.

SHOCK-ABSORBING MECHANISM.

Application filed February 18, 1926. Serial No. 23,983.

This invention relates to improvements in shock absorbing mechanisms.

One object of the invention is to provide a shock absorbing mechanism of high capacity, especially adapted for railway draft riggings, including a plurality of spring plates interposed between relatively movable followers, adapted to be flexed during compression of the mechanism to absorb shocks, wherein means is provided for holding the parts in position to prevent displacement thereof with resultant damage to the adjacent parts of the draft rigging.

Another object of the invention is to provide a mechanism of the character indicated, including a plurality of gangs of spring plates interposed between follower means adapted to be compressed between the follower means, the plates being enclosed within protecting housings and wherein inter-engaging means is employed for preventing relative displacement of the plates composing each gang, including inter-engaging means on the plates.

Other objects and advantages of the invention will more fully and clearly appear from the description and claims hereinafter following.

In the drawings forming a part of this specification, Figure 1 is a horizontal, longitudinal, sectional view of a portion of a railway draft rigging showing my improvements in connection therewith. Figure 2 is a vertical, longitudinal, sectional view, partly broken away, corresponding substantially to the line 2-2 of Figure 1. And Figure 3 is a front end, elevational view of one of the casings employed in connection with my improved mechanism, showing the gang of plates associated therewith.

In said drawings, 10-10 indicate channel-shaped center or draft sills of a railway car underframe, having front stop lugs 11-11 and rear stop lugs 12-12 secured to the inner faces thereof. A portion of the drawbar is designated by 13, to which is operatively connected a yoke 14 of well-known form. The shock absorbing mechanism proper, including the usual front and rear followers 15-15, is disposed within the yoke and the parts of the shock absorbing mechanism are supported in operative position by a detachable saddle plate 16 fixed to the draft sills.

The improved shock absorbing mechanism

proper, as shown, comprises, broadly, a pair of end casings A-A; a central casing B; a pair of intermediate casings C-C; and a plurality of gangs of spring plates D-D.

The end casings A, which are disposed at the front and rear ends of the mechanism, are of identical design. Each casing has spaced, horizontally disposed, top and bottom walls 17-17, spaced, vertically disposed side walls 18-18 and a transverse end wall 19. The end wall 19 bears directly on the corresponding follower 15. The top and bottom walls 17 are cut away at opposite sides of the longitudinal center of the mechanism to provide V-shaped projections 20 which are adapted to mate with correspondingly cut away sections on the next adjacent follower casing C when the mechanism is fully compressed. The transverse end wall 19 of each casing A has a convex, transversely disposed surface 21 on the inner side thereof. The surface 21 is vertically grooved at the center as indicated at 22 for a purpose hereinafter described.

The central casing B is provided with horizontally disposed, top and bottom walls 23-23, longitudinally disposed vertical side walls 24-24 and a transverse central web or wall 25. The wall 25 is relatively thick and has transversely disposed convex surfaces 26-26 on the opposite sides thereof. Each surface 26 is provided with a centrally disposed vertical groove 22 similar to the grooves 22 hereinbefore described in connection with the casings A. The top and bottom walls of the casing B are cut away similarly to the walls of the casing A to provide V-shaped projections 20 similar to the V-shaped projections hereinbefore described.

The two casings C are of identical design, each having horizontally disposed top and bottom walls 27-27, vertically disposed side walls 28-28, and a transversely disposed central wall 29. The wall 29 is provided with transversely disposed concave surfaces 30-30 on the opposite sides thereof. It will be evident that the transverse wall 29 is thus thickened at the opposite sides of the casing. Adjacent the side walls of the casing the transverse wall 29 is recessed at the front and rear sides thereof, as indicated at 31, to accommodate the extremities of the spring plates. The top and bottom walls of the casing C are cut away at opposite

sides of the longitudinal center thereof to provide V-shaped openings 32-32 adapted to receive the corresponding V-shaped projections 20 of the adjacent casings A and B.

5 As most clearly shown in Figures 1 and 2, the spring plates D are arranged in four gangs, a gang being interposed between each set of casings A and C, and a gang being interposed between each of the casings C 10 and the central casing B. The number of plates in each gang may be varied in accordance with the requirements to be met in the draft gear, and as herein shown each gang is preferably composed of fourteen 15 plates. The plates of each gang are identical in design, each plate being of flat rectangular form having a vertical centrally disposed corrugation 33. The corrugation 33 of each plate is nested with the corrugation of the next adjacent plate, thereby preventing lateral relative displacement of the plates of each gang. The ridges of the corrugation of the outermost plates D of the two groups disposed at the front and 25 rear ends of the mechanism are seated in the recesses 22 of the front and rear casings A, thus preventing lateral displacement of the corresponding gangs of plates with reference to the casings A. Each plate also 30 has the extreme lateral edges thereof curled over as indicated at 34, the curled edge of one plate overhanging the corresponding curled edge of the next adjacent plate of the same group. It will be evident that curved 35 surfaces are thus presented at the lateral sides of the plates of each gang. By thus curling over the edges of the plates, damage to the adjacent parts of the draft rigging by gouging is effectively prevented. It 40 is also pointed out that the inter-engaging overhanging curved edges of the plates also aid in preventing relative lateral displacement of the plates of each gang. The innermost plates of the two gangs D associated 45 with the central casing B have the ridges of the corrugations seated in the grooves 22 of the wall 25 of the casing, thus preventing lateral displacement of these two 50 groups with reference to the casings. As most clearly shown in Figure 1, the two inner gangs of plates are arranged reversely to the two outer gangs. The gangs of plates are entirely housed within the casings A, B and C, and the side and top walls of the latter preclude engagement of the edges of the plates with the draft sills, thus protecting 55 the draft sills from damage. By the arrangement of housing shown, wherein the top and bottom walls of the same are provided with mating V-shaped projections and openings, the danger of vertical displacement of the plates relatively to each other is entirely obviated as all of the plates are continuously in contact with the top and bottom walls of the casings regardless of 60 65

the relative spacing of the casings with reference to each other during the various phases of the compression and expansion strokes of the mechanism. Damage to the walls of the housings themselves is also 70 effectively prevented by holding the plates of each group against relative lateral displacement by providing the plates with the interfitting corrugations.

The operation of my improved shock absorbing mechanism is as follows: During a compression stroke, the front and rear casings A will be moved relatively toward each other, thereby compressing the four gangs of plates between the transverse walls of the casings A, B and C. As the end walls of the outer casings A are convex and the transverse central walls of the casings C have concave surfaces, the plates of the two outer 80 gangs will be correspondingly curved during compression of the mechanism. Due to the convexity and concavity of the transverse walls of the casings B and C, the plates of the two innermost gangs will also be flexed but in a direction opposite to that 85 of the plates of the two outer gangs. The described action will continue either until the actuating force is reduced or the adjacent ends of the casings A, C and B come 90 into abutment, whereupon the spring plates D will be relieved from further compression and the pressure transmitted directly through the casings, which act as a solid stop column, to the draft sills. When the actuating pressure is reduced, due to the resiliency of the flexed plates, the parts will 95 all be restored to the normal position shown in Figure 1.

While I have herein shown and described what I now consider the preferred manner of carrying out my invention, the same is merely illustrative, and I contemplate all changes and modifications that come within the scope of the claims appended hereto.

I claim:

1. In a shock absorbing mechanism, the combination with front and rear, relatively movable follower casings having end walls provided with curved interior surfaces; of a casing interposed between said follower casings, said last named casing having a transverse central wall provided with curved surfaces on the opposite sides thereof; a plurality of spring plates housed within said casings, said plates being arranged in groups and the end plates of each group co-operating with the curved walls of two of said casings respectively; and co-acting means on the plates of each gang for preventing relative lateral displacement of the plates composing said gangs.

2. In a shock absorbing mechanism, the combination with relatively movable followers having curved bearing surfaces; of a plurality of intermediate followers having

reversely curved bearing surfaces on the front and rear sides thereof, said opposed bearing surfaces of said mechanism being curved in the same direction; a group of substantially flat spring plates interposed between each set of opposed bearing surfaces.

3. In a shock absorbing mechanism for railway draft riggings, the combination with relatively movable follower means having curved bearing surfaces; of a plurality of rectangular flat spring plates interposed between said follower means, said plates be-

ing flexed upon relative approach of said follower means, the side edges of all of said plates being curled over in the same direction, the curved edges of each plate overhanging the adjacent plate, thereby presenting curved surfaces at the side of the plates to prevent damage to the adjacent members of the draft rigging.

In witness that I claim the foregoing I have hereunto subscribed my name this 15th day of February 1926.

JOHN F. O'CONNOR.
